CLAIM

The ornamental design for a LED tube light, as shown and described above.

DESCRIPTION

FIG. 1 is a perspective view of a LED tube light showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The shade lines (straight solid lines) in the figures show surface contour and material composition, but not surface ornamentation. The broken lines are environmental and form no part of the claimed design, which include six circular structures shown in broken lines in FIGS. 1, 6, and 7.
